FLUID SWITCH

Application filed June 23, 1928, Serial No. 287,832, and in Germany September 16, 1927.

This invention is directed to an improvement in mercury switches in which the circuit closing member is in the form of a perforated strip arranged between the spaced terminals of the circuits and serving, when in one position, to admit a body of mercury to electrically connect said terminals.

The main difficulty in switches of this character is to so arrange the movable member or perforated strip as to prevent accumulation of the mercury beneath the same while at the same time permitting the necessary movement of the strip for switch purposes. Furthermore, as heretofore proposed, such switches require a comparatively large quantity of mercury as the entire switch chamber must be filled with mercury to provide the proper connection.

The primary object of the present invention is the provision of means whereby the perforated strip or movable switch member is so mounted in the switch construction as to insure such contact with the operating part as to prevent mercury leakage beneath the strip, provision being made for a reserve quantity of mercury above the strip.

A further object of the invention is the provision of a cut-off for breaking the current connections without the necessity of moving the perforated strip or withdrawing the mercury.

The invention is illustrated in the accompanying drawings, in which:

Figure 1 is a broken longitudinal section through a switch constructed in accordance with the present invention.

Figure 2 is a transverse section of the same showing a slightly modified construction, the cut-off being in operative position.

Figure 3 is a similar view, the cut-off being inoperative position.

The improved switch includes a chamber-like construction having a base plate *a* which forms the base of the switch and through which conductor terminals *b* are extended, their ends lying flush with the upper surface of the base plate. A guide *g* overlies the base plate *a*, being arranged in spaced relation to the latter to provide a narrow passage through which the movable switch member

operates. Beyond the base plate, the switch is formed to provide a depressed channel or chamber to receive a suitable quantity of mercury, indicated at *i*, and it is to be particularly noted, as will be evident from the drawings, that this mercury is not in sufficient quantity to normally reach the narrow passage between the base plate *a* and the guide *g*.

The movable member of the switch is in the form of a more or less flexible strip *d*, which if desired may be endless, and which is adapted to pass around rollers *e* supported from the guide *g* and arranged in a mercury chamber at the respective ends of the switch. This movable member or strip is formed with perforations, indicated at *f*, and these perforations may follow any regular or desired order; that is to say, by the arrangement of the perforations, any particular relation of terminals *b* may be energized in a particular position of the movable member, as is well understood in switches of this type.

An essential and desirable characteristic of switches of this type is the necessity for preventing the mercury from accumulating between the movable member and base plate, as if this condition is permitted to exist, short-circuiting or undesirable switch connections will necessarily follow. In order to provide for this desirable function, the movable member of the switch, in being led from the upper surface of the base plate to and around the rollers *e*, passes over the downwardly inclined wall section *a'*. This wall section *a'* forms an angular relation with the surface of the base plate, so that the strip or movable member is drawn snugly over the rounded corner or shoulder formed by the juncture of the base plate and inclined wall *a'*, thus tending to maintain the movable strip in a comparatively tight fit with the upper surface of the base plate.

The volume of mercury is normally not sufficient to reach the space between the base plate and guide and when the switch is desired for use, the level of the mercury is increased through the medium of a block *k* arranged in the mercury chamber and adapted to be depressed manually at will. Obviously, the depression of this block tends to raise the

normal level of the mercury in the chamber so that it will reach the space between the base plate *a* and the guide *g* and so pass through the perforations *f* in the movable member to complete the electric connection 5 between the guide *g* and those terminals *b* in the base plate with which the perforations *f* in the movable member or strip are in register. The mercury chamber has a depending 10 partition *p* around which the mercury is directed in the operation of the block *k* to prevent current impulses.

To provide a reserve supply of mercury overlying the movable switch member *d*, the 15 guide *g* is formed with grooves *h* which may extend longitudinally or transversely, or both, of the guide and open to the space between the guide and base plate *a*. This reserve supply of mercury insures an accurate 20 filling of the perforations *f* of the movable strip in all switch conditions.

To provide for cutting off the switch without the necessity of moving the strip *d*, there is arranged between said strip and the base 25 plate a cut-off *n* formed with perforations *o* to register, in one position of the cut-off, with the terminals of the conductors *b* extending through the base plate. The cut-off *n* has an accurate sliding fit with the base plate surface 30 and the movable strip bears snugly upon the upper surface of the cut-off as illustrated. Obviously, with the cut-off in position to register with the terminals, the movable strip *d* controls the circuiting arrangements in accordance 35 with positions of the perforations *f* in said strip, while with the cut-off moved so that its openings *o* are out of registry with the terminals of conductors *b*, the circuit is broken.

40 The switch is designed for any and all uses to which such a switch may be put, it being here shown as controlling the various illuminating members of a sign *c* with an energizing source indicated at *B*, one side of which 45 is in connection with the guide *g*.

What I claim to be new is:

1. A fluid switch having a base plate, terminal conductors leading through the base plate and terminating flush with the surface 50 thereof, the switch including a mercury chamber arranged beyond the base plate, a guide plate overlying the base plate and forming a common circuiting terminal, a perforate strip movable through the space 55 between the guide and base plate, and means for raising the level of the mercury at will in the chamber to and above the space between the base plate and guide.

2. A switch including a base plate and a 60 mercury receiving chamber therebeyond, circuiting conductors leading through the base plate, a guide forming a common circuit terminal and arranged in spaced relation to the base plate, means operative in the space 65 between the guide and base plate for deter-

mining circuiting conditions, the normal volume of mercury in the chamber being insufficient to reach said space, and means whereby the level of the mercury in the chamber may be raised and lowered at will. 70

3. A switch including a base plate and a mercury receiving chamber therebeyond, circuiting conductors leading through the base plate, a guide forming a common circuit terminal and arranged in spaced relation to the base plate, means operative in the space between the guide and base plate for determining circuiting conditions, the normal volume of mercury in the chamber being insufficient to reach said space, and a block operative in the chamber to raise and lower the level of the mercury at will. 75 80

4. A fluid switch comprising a base plate, a mercury reservoir below and beyond said base plate, circuiting conductors leading through said base plate, a guide forming a common circuit terminal and arranged in spaced relation to said base plate, means operative in the space between the guide and base plate for determining circuiting conditions, a circuiting strip adapted to pass thru the reservoir and thence over the base plate, the normal level of the mercury in the reservoir being just below that of the strip at the point of passing over the base plate, and means for raising the level of the mercury in the reservoir. 85 90 95

In testimony whereof I affix my signature.
